UNITED STATES PATENT OFFICE.

JEAN LIEBER, OF LAUSANNE, SWITZERLAND.

LIQUID-FUEL BURNER.

Application filed March 24, 1921. Serial No. 455,373.

(GRANTED UNDER THE PROVISIONS OF THE ACT OF MARCH 3, 1921, 41 STAT. L., 1313.)

To all whom it may concern:

Be it known that I, JEAN LIEBER, a citizen of the Republic of Switzerland, residing at Lausanne, Switzerland, have invented certain new and useful Improvements in Liquid-Fuel Burners (for which applications for patents have been filed in Switzerland October 24, 1913, Patent No. 66206; Germany, October 31, 1913, Patent No. 288651; 10 England, November 3, 1913, Patent No. 22058/13; France, October 19, 1914, Patent No. 476,344; Sweden, October 22, 1914, Patent No. 40115; Italy, November 11, 1915, Patent No. 38/454; Russia, January 9/22, 15 1917, Application No. 71133; Switzerland, April 15, 1920, Patent No. 87900; Czechoslovakia, June 30, 1920, Application No. P4938-20; Poland, July 5, 1920, Application No. 10103; Belgium, July 16, 1920, Application No. 231,760); and I do hereby declare the following to be a clear, full, and exact description of the invention, such as will enable others skilled in the art to which it appertains to make and use the same, reference being had to the accompanying drawing, and to letters or figures of reference marked thereon, which form a part of this specification.

It is known that a flame of considerable 30 expanse is used for heating, welding and hard-soldering the parts of machines and other large metal objects, especially for welding cast-iron objects. It has been attempted to construct large burners for large 35 flames, but the result was that these burners, owing to their size, were not easy to manipulate and in comparison with the heat effect obtained therefrom, were also uneconomical. Further, when using such 40 burners the objects, especially the cast-iron pieces, are easily cracked. The pieces to be welded were then pre-heated in an open forge furnace and heated from above by means of a burner while lying in the furnace. 45 In this case, however, the drawback arose that the burner did not act properly because the furnace absorbed too much oxygen from the surrounding air and therefore the air

entering the front of the burner did not contain sufficient oxygen. This air was also 50 not pure enough as it contained burnt gases.

These drawbacks are overcome by the apparatus of the present application. Said apparatus consists of a frame from which projects a torch, which is adjustable about 55 the horizontal axis in various directions and is fed with air from behind.

Provision is made for a regulating and closing device for said torch which is preferably constructed independently of said 60 torch. The frame may be transportable and may be furnished with a receptacle for the fuel and said receptacle may act as a counterweight for the projecting torch. The adjustment of the torch in various directions may be obtained by adjusting the position of the frame as a whole or by adjusting the position of a cantilevered part of the frame, at the end of which part the torch is mounted, relatively to the other part of 70 the frame and means adapted to effect such adjustments may be carried out in many ways, a few constructional examples will be described hereinafter.

The front part of the torch may be surrounded by a pre-heating chamber which is connected with the torch-nozzle and with a pipe leading to the axis of rotation of the torch, said pipe may be furnished with a needle-valve, adjustable by a handle, which 80 handle may be removed from the source of heat. The pre-heater and the torch may be surrounded by a jacket. The rotation of the torch about the horizontal axis may be obtained by means of a worm-gearing rotatable by hand. Further the torch may be provided with a removable cap in order 85 to ignite and pre-heat the fuel discharged by the orifice of the pipe.

Several constructions of the apparatus 90 according to this invention are illustrated by way of example in the accompanying drawings, in which:

Fig. 1 is a side elevation of a first constructional example,

Fig. 2 is a plan,

- Fig. 3 is a section of the torch drawn to a larger scale, and
- Figs. 4 and 5 are details in section.
- Fig. 6 is a side elevation of a second constructional example,
- Fig. 7 is a plan view and
- Fig. 8 is a view seen from the left hand side of the torch and of part of the frame supporting the former.
- 10 Figs. 9, 10 and 11 are details of torch construction.
- Referring at first to the constructional example illustrated in Figs. 1-3, 1 is a tank for the fuel, especially petrol. This 15 tank is arranged on a frame 3 supported on the wheels 2. An upright, in the form of a tube 4, is rigidly connected with the frame 3 and is provided at the top with a nut 5 (Fig. 5).
- 20 A spindle 6 which is provided at the top above the head 7 with a bevel wheel 8, is screwed into the nut. The head 7 rests on a ring 9 which is connected with the spindle 6. A tube 10 is rigidly secured to 25 this head 7 and at the bottom rests loosely on the ring 11. The whole is guided in a sleeve 12 which is rigidly secured to stiffening bars 13. A segment 14 is rigidly connected with the head 7 in which segment a bevel wheel 15 engaging with the toothed wheel 8 is mounted and may be rotated by hand by means of a crank 16.
- Further, one or two angle iron arms are rotatably arranged on the head 7. A worm 20, rotatable in a stiffening stay 18 of the arms 17 and provided with a crank 19, engages in the toothed rim 21 of the segment 14, so that by means of the crank 19, the angle position of the arm 17 may be adjusted to the horizontal.
- 40 The torch rests between the front ends of the arms 17 and is held by means of pins 22. One pin carries a fast worm wheel 23 into which the worm 24 engages, this worm is rotatably mounted on the arm 17 and may be rotated by means of a hand wheel 25 so that the torch may be adjusted at an angle to the horizontal. The torch possesses a front part 26 and a back part 27 which latter is provided with a nozzle 28 and the openings 29 for the air. The head 26, 27 of the torch is encased in a jacket 30. Between the jacket 30 and the front part 26, the vaporizing chamber 31 is arranged, 55 which latter is connected with the nozzle 28 by means of a tube 32. By means of a tube 33 the vaporizing chamber 31 is connected with the feeding pipe 34 for the petrol, which pipe penetrates one of the trunnion pins 22 and is partially mounted in the arm 17. A regulating apparatus is arranged in this pipe 34 (Figs. 3 and 4). A valve needle 35 is provided with thread at one end and is screwed thereby into the end 36 (formed as a nut) of the bolt 37, which latter is rigidly connected with a hand wheel 38. The valve needle 35 may be moved in an axial direction by rotating the hand wheel 38. For this purpose, a pin 35' is arranged in the needle 35 towards one end, 70 and the projecting ends of the pin engage the slotted end of the fuel pipe 34. In this way the needle is prevented from rotating but is allowed to move axially. 39 is a cap which may be placed on the front of the cylinder 30 and may be prevented from falling off by any desirable means, for instance, by means of a bayonet lock.
- The operation of this apparatus is as follows:
- After petrol has been pumped from the reservoir 1 into pre-heater 31 by means of a pump not illustrated in this constructional example, the torch is adjusted by means of a hand wheel 25 so that its axis is vertical. 85 Petrol is then allowed to enter into the cap 39 through the nozzle 28 and is ignited whereby the pre-heating of the torch and the beginning of the evaporation takes place by the fuel of the feeding pipe, without adding fuel from an open receptacle which latter operation is tiresome, dangerous and wastes time.
- After removing the cap 39, the frame 3 is moved towards the forge furnace in which the cast pieces to be welded are lying, and the head of the torch is now adjusted by means of the hand wheel 25 and the cranks 16 and 19. The adjustment of the torch by means of the hand wheel 25 may be performed before the burner has been brought up to the furnace, so that when it is at the furnace, the workman has only to actuate the adjusting members 16, 19, 38 which are situated a long way from the flame and 105 close together. The arrangement that the feeding of the air to the torch is performed from the back renders it possible to direct fresh air to the torch which air has not been in contact with the furnace and therefore contains the necessary oxygen for producing an intensive and rational combustion. The arrangement where the regulating apparatus is not situated on the torch, prevents said regulating apparatus from being too highly heated and thus facilitates the manipulation, prevents the gas from striking backwards and renders therewith the disadvantageous heating of the feeding pipe as well as the dangerous penetration of 110 the pure gases in the fuel tank 1, impossible.
- 115 In the constructional example of the burner illustrated in Figs. 6-8, 51 denotes the tank for the fuel, which tank is carried on a frame 52, to which the axle 53 of two large lateral wheels 54 are fixed, the tank 51 being arranged between said two wheels 54. In front of the fuel tank a small wheel 55 is provided rotatably mounted on the frame 52. It is evident that this 120

small wheel might also be arranged behind the tank or two small wheels might be provided, but in every case the axis of rotation of said small wheel or wheels are parallel to the axis of rotation of the large wheels. The torch 56 is rotatably mounted about a horizontal axis fitted to the end of a cantilevered frame. The frame consists of two forks, a lower fork 57 and an upper fork 58 which are connected to each other by a pin 59 secured to the upper fork 58 being inserted in a bush 60 provided on the lower fork 57. By this means the upper fork can be turned relatively to the lower fork 57 around an axis passing in the longitudinal direction of the cantilevered frame. A locking screw 61 serves to fix the fork 58 in any angular position of this rotation. The lower fork is swingably mounted around the axles 53 of the wheels 54, so that the whole cantilevered frame can be adjusted in a vertical plane. In order to fix or lock the cantilevered frame in angular positions around the fulcrums 53 a segment 62 is fixed to the frame 52 and a friction-ratchet 63 fitted with a handle and engaging with said segment is secured to the lower fork 57 of the cantilevered frame. A spring 64 causes the friction-ratchet 63 to engage with the segment 62 and the cantilevered weight of the torch 56 tends to increase the locking action. Instead of the smooth segment 62 and the friction-ratchet 63 a toothed segment might be made use of, or the segment might be constructed as part of a worm wheel with which a worm fixed to the fork 57 might coact. The segment could also be fixed to the fork 57 and the friction-ratchet to the frame 52 for obtaining the same locking effect. The fuel of the tank is supplied by means of a flexible pipe 65 to a regulating apparatus 66 of the same type as has been described with the first constructional example. The tank is further provided with an air pump of known type, the handle 67 of which is seen projecting above the tank, the pump serving to apply pressure to the fuel contained in the tank. The cylinder of the pump, to which the valve chamber is welded is welded to the tank. The upper edge 82 of the cylinder projects above the tank and the valve chamber 83 is seen projecting laterally at the lower end of the tank. By this arrangement a tedious tightening is rendered superfluous and the plunger rod can easily be inserted from above and taken out and the valve can be inspected and erected from the outside. From the regulating device 66 the fuel is supplied to the torch 56 through the hollow pin 68 (Fig. 9). The torch illustrated in Fig. 9 resembles that shown in Fig. 3 but is of a simplified design. The vaporizing chamber 69 is integral with the two trunnion pins 68 and 70, by means of which the torch is rotatably mounted in the end parts of the upper fork 58. There is no jacket used as is the case in the torch shown in Fig. 3 and the cover of the torch is rigidly fixed to the outer wall of the vaporizing chamber 69. The fuel passing through the hollow pin 68 may be led into the vaporizing chamber 69 by means of a pipe 71, (or through a hole connecting the hollow pin 68 with the chamber 69), and from that chamber by means of a further pipe 72 to the concentrically arranged nozzle 73, which corresponds to the nozzle 28 shown in Fig. 3. This nozzle is provided with a valve needle 74 actuated by a hand lever 75 for cleaning the nozzle in an easy and efficient manner. The air for combustion enters at the rear part i. e. the bell-mouth shaped opening of the cover in the axial direction of the torch. A hand lever 76 is further provided by which a turning motion of the torch around the axles 68 and 70 can be effected.

Another construction of a torch is shown in Figs. 10 and 11, which differs from the torch above described in as much as there is no vaporizing chamber provided. For vaporizing purposes compressed air is admitted through a nozzle 77 arranged in the center of the torch, whereas the nozzle 78 for supplying the fuel is arranged laterally. The fuel passes again from the regulating device 66 through a bore provided in the pin 68 and the compressed air enters through a bore provided in the opposite pin 70. The pins or axles 68 and 70 are the lateral extensions of a U-shaped body 79 of a rectangular cross-section to which the cover for the torch is rigidly connected. The air for combustion is again admitted at the back of the torch.

The constructional example illustrated in Figs. 6-8 presents the advantage of a simple and compendious design. The lifting and lowering of the torch is easily and quickly effected and the burner may be so adjusted, as is seen in Fig. 1 in dotted lines, that it can act upon parts situated in a ditch 80 for instance on sleepers, rails and the like. The torch may be easily turned around a horizontal axis by means of the hand lever 76. The carriage is easily dirigible especially when the front wheels are lifted off the ground by pressing on the handle 81 and the movability of this construction is greater than that shown in Figs. 1-3.

I claim:

1. In a liquid fuel torch, a nozzle, a cover having an outwardly flared rear end through which atmospheric air is admitted in the longitudinal direction of the torch, a member arranged inside said cover adapted to support said cover and said nozzle, trunnion

- pins on said member to permit of a swingable mounting of said torch, and means to supply fuel to said nozzle through a central bore in one of the trunnion pins.
5. 2. In a liquid fuel torch, a nozzle, a cover having an outwardly flared rear end through which atmospheric air is admitted, a member adapted to support said cover and said nozzle, a chamber for pre-heating the fuel provided in said member, a connection between said chamber and said nozzle, trunnion pins on said member to permit of a swingable mounting of said torch, and means to supply fuel to said chamber through a central bore in one of the trunnion pins.
10. 3. In a liquid fuel burner, the combination with a container for fuel under pressure, of a torch to which atmospheric air for combustion is admitted from behind, a pivotally mounted cantilevered frame to the outer end of which said torch is mounted rotatably about a horizontal axis, a frame for carrying said container and the pivots for said cantilevered means, said frame being supported on wheels, means adapted to adjust said cantilevered frame in positions of its movement around said pivots, and means to supply fuel from the container to said torch.
15. 4. In a liquid fuel burner, the combination with a container for fuel under pressure, of a torch to which atmospheric air for combustion is admitted from behind, a cantilevered frame to the outer end of which said torch is mounted, a frame to which said cantilevered frame is pivotally connected supporting said container and being supported on wheels, a segment coaxially arranged to said pivots and fixed to said
20. 5. In a liquid fuel burner, the combination with a container for fuel under pressure, of a torch to which atmospheric air for combustion is admitted from behind, a cantilevered frame to the upper bifurcated part of which said torch is turnably mounted, a frame to which the lower bifurcated part of said cantilevered frame is pivotally connected and adapted to support said container, means interposed between said two bifurcated parts of the cantilevered frame to permit of an adjustment of the upper part relatively to the lower part around the longitudinal axis of said cantilevered frame, a segment coaxially arranged to said pivots and fixed to said frame, means operatively connected to said cantilevered frame and cooperating with said segment and allowing of fixing said arm to any angular position along said segment, and means to supply fuel from the container to said torch.
25. 6. In a liquid fuel torch having a flared rearward end and a contracted front end; trunnions on which the torch is mounted, the axis of the trunnions being arranged at right angles to the longitudinal axis of the torch and intermediate the ends of the latter, an entraining nozzle in the longitudinal axis of the torch and a fuel supply nozzle directed across the jet of the entraining nozzle, both nozzles connected to and supplied through said trunnions.
30. In testimony that I claim the foregoing as my invention, I have signed my name.
35. JEAN LIEBER.
